TOY FIGURE OR SIMILAR ARTICLE

Filed July 12, 1950

FIG. 1

FIG. 3

Inventor
Alfred Pinterally

by The Firm of Charles H. Miller Atty's

UNITED STATES PATENT OFFICE

163,765

TOY FIGURE OR SIMILAR ARTICLE

Alfred Pinterally, Chicago, Ill.

Application July 12, 1950, Serial No. 11,093

Term of patent 14 years

(Cl. D34—2)

To all whom it may concern:

Be it known that I, Alfred Pinterally, a citizen of the United States, and a resident of the city of Chicago, in the county of Cook and State of Illinois, have invented a new, original, and ornamental Design for a Toy Figure or Similar Article, of which the following is a specification, reference being had to the accompanying drawing, forming a part thereof.

On the drawing:

I claim:

The ornamental design for a toy figure or similar article, substantially as shown.

ALFRED PINTERALLY.
